UNITED STATES PATENT OFFICE.

JOHN O. NEIKIRK, OF LOMBARD, ILLINOIS.

DESIGN FOR A DRAFT-GEAR YOKE.

51,531.

Specification for Design.

Patented Nov. 27, 1917.

Application filed October 1, 1917. Serial No. 194,294. Term of patent 14 years.

To all whom it may concern:

Be it known that I, JOHN O. NEIKIRK, a citizen of the United States, residing at Lombard, in the county of DuPage and State of Illinois, have invented a new, original, and ornamental Design for Draft-Gear Yokes, of which the following is a specification, reference being had to the accompanying drawing, forming part thereof.

The figure is a perspective view of a draft gear yoke showing my new design.

I claim:

The ornamental design for a draft gear yoke, as shown.

JOHN O. NEIKIRK.
